UNITED STATES PATENT OFFICE.

JAMES C. OLLARD, OF TACOMA, WASHINGTON.

CLUTCH.

1,306,230.

Specification of Letters Patent. Patented June 10, 1919.

Application filed August 22, 1917. Serial No. 187,663.

To all whom it may concern:

Be it known that I, JAMES C. OLLARD, a citizen of the United States, residing at Tacoma, in the county of Pierce, State of Washington, have invented certain new and useful Improvements in Clutches, of which the following is a specification.

This invention relates to devices whereby a rotating shaft may be secured to another shaft, or released therefrom, to rotate it whenever desired, and has special reference to clutches for use in automobiles and other similar vehicles and uses.

The objects of the invention are, first, to produce a very light, compact and strong clutching mechanism; second, to provide an improved means of gaining great leverage in the clamping mechanism whereby a very light clutch-spring may be used and therefore the wear on the clutch releasing mechanism may be materially reduced; third, to provide a single adjusting means of improved design to take up the wear on all the clutching mechanism; and fourth, to provide simple and effective means whereby said adjusting means may be locked in any adjusted position.

I attain these and other objects by the devices, mechanisms, and arrangements illustrated in the accompanying drawings, in which—

Figure 1 is a section of my improved clutch on a plane parallel to the axis of rotation, showing the parts in clutching position; Fig. 2 is a front elevation thereof; Fig. 3 is a section, similar to Fig. 1, showing the parts in released position; Fig. 4 is a perspective view of one of the levers; Fig. 5 is a similar view of one of the keepers; Fig. 6 is a front elevation of the lever-carrying disk; Fig. 7 is a front elevation of the movable clamping disk; and Fig. 8 is a side elevation showing the clutch mounted on a power shaft.

Similar numerals of reference refer to similar parts throughout the several views.

The driving shaft 1 is provided with the usual circular flange 2 at its end, to which the flywheel, or main body of the clutch, is firmly secured by bolts. This flywheel con-

sists of a disk 3, through which the said bolts pass, surrounded by a rim 4. This rim 4 is not placed symmetrically over the disk 3 but extends to one side thereof so as to form a hollow body wherein the clutching mechanism is mounted. The disk 3 is also provided with a small central hole 5 adapted to receive the reduced end 6 of the driven shaft 7.

A ring-shaped lining 8 fits in the inner surface of the rim 4 and is fixedly secured thereto by means of screws 9 which pass through an outward-extending flange 10 thereof, which flange fits on the vertical edge of said rim 4. The inner surface of the lining 8 is screw-threaded, as shown. A key-slot 11 is cut in the lining 8, through the screw-threads thereof, parallel with the axis of the shafts 1 and 7.

An adjusting ring 12, whose outer surface is screw-threaded to fit the threads in the lining 8, screws therein. This ring 12 is split by a slot 13, parallel with its axis, and a tapered locking screw stud 14 is screwed into the sides of said slot 13 so that when said stud 14 is screwed down, it expands said ring 12 and locks it in the lining 8 so that it can not turn therein and so that when said stud 14 is screwed outward, said ring 12 is allowed to spring back and is then free to be turned in the ring 8 to adjust its position axially in the mechanism. A lock nut 15 is provided for the screw 14. The ring 12 is provided with a series of holes 16 adapted to be engaged by a suitable turning wrench whereby it may be adjusted. An inward-extending circular flange 17 is formed at the inner end of the ring 12, said flange being adapted to be engaged by the hereinafter described keepers or lugs 18.

The carrying disk 19 (Fig. 6) fits in the lining ring 8 and has a key 20 which fits in the key-slot 11 therein so that said disk 19 is free to move axially but cannot turn therein. A plurality of keepers or lugs 18 are secured to the face of the disk 19 and are shaped to engage the said flange 17 on the adjusting ring 12. The keepers 18 connect the carrying disk 19 with the adjusting ring 12, which, when unlocked, is permitted to

rotate freely to adjust the carrying plate inwardly and outwardly to lift the plate or push it down as required. The face of the disk 19 is also provided with a plurality 5 (preferably three) pairs of lugs 21 extending therefrom and adapted to receive the fulcrum pins, of the hereinafter described levers 22, and an opening 23 is provided in said disk 19 between the lugs 21, forming a 10 pair, through which a portion of said levers projects. A pin 24 extends out from the face of the disk 19 and engages the hereinafter described sleeve 25 whereby said sleeve 25 is prevented from turning relatively to said 15 disk 19 but is allowed free axial motion relatively thereto. The opposite or inner face of the disk 19 is provided with a concentric cylindrical flange 26 from which extend three cylindrical keys 27 (one only is 20 shown in Fig. 1) adapted to engage in suitable keyways 28 in the hereinafter described movable clamping disk 29 whereby said disk is prevented from having relative 25 rotary motion while it is free to have relative axial motion.

The movable clamping disk 29 (Fig. 7) has a large central hole 30 with three keyways 28 opening therefrom wherein the above mentioned keys 27 engage. Its outer 30 face, adjacent the disk 19, is provided with hardened steel contact disks 31, located in line with the openings 23 in the disk 19, and adapted to receive the pressure from that portion of the levers 22 which projects 35 therethrough, said disks 31 having central stems projecting through the clamping disk 29. The opposite or inner face of the disk 29 is provided with a friction surface near its rim.

40 The driven shaft 7 extends into the space between the disk 3 of the flywheel and the carrying disk 19 and has a driven friction disk 32 securely fastened thereto, said disk being slightly smaller in diameter than the 45 inside of the rim 4.

Two intermediate friction rings 33, of the same diameter as said disk 32, are interposed between the faces of said disk 32 and the driving friction disks 3 and 29, said 50 disks 33 being made of suitable material.

Referring now to the means for actuating said clutching mechanism; it will be seen that the carrying disk 19 is provided with a central cylindrical sleeve 34 extending outward therefrom, through which the driven shaft 7 passes. This sleeve 34 is firmly secured to the disk 19 and carries a nut 35 at its outer end. The above-mentioned sleeve 25 fits outside of the sleeve 34 and 55 moves freely axially thereon but cannot turn relatively thereto. The outer end of the sleeve 25 is formed with an enlarged cavity 36 wherein the light clamping spring 37 is mounted, said spring being compressed between the nut 35 and the shoulder at the in-

ner end of the cavity 36 so as always to tend to force said sleeve 25 toward the disk 19 (Fig. 1). Three lugs 38 extend radially 70 out from the sleeve 25 and are adapted to engage the operating levers 22.

These levers 22 (Figs. 1, 2, 3 and 4) are provided, at their head ends, with holes 39 through which the fulcrum pins pass and by which they are attached to the lugs 21 on the face of the disk 19. The head is also provided with an inward extension adapted to pass through the opening 23 in the disk 19 and carrying a hardened steel contact piece 40 which bears on the hardened steel disk 31 of the movable disk 29. A spring cavity 41 is also provided in the lever 22, near the head thereof, and adapted to receive and hold a retrieving spring 42 which presses against the disk 19 and tends to counteract the above-mentioned clamping spring 37. 75 The opposite end of the lever 22 is engaged by the above lug 38 of the sleeve 25. Referring to the elevation shown in Fig. 2, it is clearly seen that these levers 22 are also of special shape relatively to the plane at right-angles to the axis of rotation. The lugs 21 80 of the disk 19 are arranged so that the center line, of the space between the lugs forming a pair, is radial and the head of said lever, being mounted between these lugs, is therefore 85 also radial. Then again, it will be seen that the lug 38 of the sleeve 25 extends therefrom on a radial line drawn at right-angles to the radial line of said lever head, and that the lever shank is given two opposite bends so 90 that the end of said shank is parallel to the head thereof and engages said lug 38 on a line parallel with the radial center line of the head of the lever and tangential to said sleeve 25 at said lug. This arrangement 95 gives a great leverage for the force of the spring 37, as applied to the clamping disk 29 through the contact piece 40, without any twisting action such as is had if the lever head be not arranged radially.

100 The sleeve 25 may be moved to release the clutch, against the action of the spring 37, by means of a foot lever 45, suitably supported near the clutch and having slotted forked ends engaging the trunnions 43 of the ring 44 which is suitably mounted on the 105 said sleeve 25 in such manner as to permit said sleeve 25 to turn therein but to transmit thereto any axial motion which may be given by said foot lever.

110 In Figs. 1 and 8 the clutch is shown in clutching position, the sleeve 25 being actuated by the coiled spring to force the levers 22 inwardly. The clutch is unclutched by operating the foot lever to lift the sleeve 25 115 and permit the springs 42 to move the levers outwardly and release the clamping disk 29.

Having therefore described my invention, what I claim is:

1. In a shaft clutch, the combination with 120

- a rotating shaft carrying a hollow clutch body; of a lining secured in said clutch body and having its inner surface screw-threaded; a split ring screwing into said lining and adapted to be relatively turned therein to adjust the clutching mechanism; a tapered stud screwed into the split portion of said ring to expand it and thereby to lock it in adjusted position in said lining; a driven shaft having a clutch surface within said hollow clutch body, but free therein; and clutch mechanism carried by said adjusting ring but movable only axially relatively to said rotating shaft and adapted to engage the clutch surface of said driven shaft to rotate it.
2. In a shaft clutch, the combination with a rotating shaft carrying a hollow clutch body; of a lining secured in said clutch body and having its inner surface screw-threaded and keysloshed; a split ring screwing into said lining and adapted to be relatively turned therein to adjust the clutching mechanism; means for expanding said split ring to lock it in adjusted position in said lining; a driven shaft having a clutch surface within said hollow clutch body, but free therein; a carrying plate loosely secured to said ring and having a key engaging the key slot in said lining, whereby said plate is prevented from rotary motion relatively to said hollow clutch body but is given axial motion relatively thereto by the adjustment of said split ring; and clutch mechanism carried by said carrying plate and axially movable relatively thereto whereby said clutch surface of the driven shaft is engaged to rotate it.
3. In a shaft clutch, the combination with a driving shaft carrying a hollow clutch body and a driven shaft having a clutch surface mounted within said hollow body; of a sleeve mounted on and axially movable on said driven shaft and rotatively connected to said driving shaft; radial lugs extending from said sleeve; a carrying disk mounted in said hollow clutch body; clutching mechanism rotating with said driving shaft and mounted between said carrying disk and said clutch surface of the driven shaft and adapted to engage and rotate said clutch surface; and levers mounted on said carrying disk and engaging said clutching mechanism to operate it, each of said levers being radially mounted at its head or pivoted end and having its shank offset but parallel with said head end whereby the end of said shank is engaged by said lug on the sleeve to operate it and whereby it lies tangential to said sleeve.
4. In a shaft clutch, an axially movable clutch body having a central hole therein with suitable keyways in the inner edge of said clutch body, outward from said hole, an axially immovable carrying body having a central boss passing freely through the said hole in said movable clutch body, and means mounted on said carrying body and engaging said clutch body and adapted to move said clutch body axially relatively to said carrying body; in combination with cylindrical inserts forming keys, each having its axis parallel with the axis of said clutch body, said inserts being partially embedded in the outer face of said boss and extending therefrom to engage the keyways in said movable clutch body whereby relative rotation between said bodies is prevented.
5. In a shaft clutch, the combination with a rotating shaft and a hollow clutch body carried by the same, of a lining secured in said clutch body and having its inner surface screw-threaded, a split ring screwing into said lining and adapted to be relatively turned therein, a driven shaft having a clutch surface within said hollow clutch body but free therein, clutch mechanism carried by said adjusting ring but movable only axially relative to said rotating shaft and adapted to engage the clutch surface of said driven shaft to rotate it and means for expanding the adjusting ring to lock the same in its adjustment.
6. In a shaft clutch, the combination with a driven shaft having a clutch member, a hollow clutch body, a relatively adjustable carrying plate, an adjusting ring connecting the carrying plate with the body and swiveled to one of the parts and having a threaded engagement with the other, a movable clamping member located within the hollow body and co-acting with the body to clamp the clutch member of the driven shaft, and means carried by the said plate for actuating the movable clutch member.
7. In a shaft clutch, the combination with a driven shaft having a clutch member, a hollow clutch body, a relatively adjustable carrying plate, an adjusting ring connecting the carrying plate with the body and swiveled to one of the parts and having a threaded engagement with the other, a movable clamping member located within the hollow body and co-acting with the body to clamp the clutch member of the driven shaft, and means carried by the said plate and arranged exteriorly thereof for actuating the movable clutch member.
8. In a shaft clutch, the combination with a driven shaft having a clutch member, a hollow clutch body, a relatively adjustable carrying plate, an adjusting ring connecting the carrying plate with the body and swiveled to one of the parts and having a threaded engagement with the other, a movable clamping member located within the hollow body and co-acting with the body to clamp the clutch member of the driven shaft, and clutch members mounted on the exterior of the carrying plate and having arms ex-

tending through the same for actuating the movable clutch member.

9. In a shaft clutch, the combination with a driven shaft having a clutch member, a hollow clutch body, a relatively adjustable carrying plate, an adjusting ring having a swiveled connection with the carrying plate and a threaded engagement with the hollow

body, a movable clamping member located within the hollow body and co-acting with the body to clamp the clutch member of the driven shaft, and clutch members mounted on the exterior of the carrying plate and having arms extending through the same for actuating the movable clutch member. 10 15

JAMES C. OLLARD.
